PUMPING SYSTEM

Original Filed Aug. 31, 1927

UNITED STATES PATENT OFFICE

JOHN OLIPHANT, OF CHICAGO, ILLINOIS, ASSIGNOR TO SULLIVAN MACHINERY COMPANY, A CORPORATION OF MASSACHUSETTS

PUMPING SYSTEM

Application filed August 31, 1927, Serial No. 216,661. Renewed March 13, 1931.

My invention relates to pumping systems and more particularly to displacement pumps.

An object of my invention is to provide an improved pumping apparatus. Another object is to provide an improved pumping apparatus particularly adapted for use where it is desired to discharge into elevated tanks. A further object is to provide improved pumping mechanism which may be operated either as a displacement pump or as an air lift pump. A further object is to provide improved adjustable automatic controlling mechanism for a displacement pump. These and other objects and advantages will, however, subsequently more fully appear.

In the accompanying drawings I have shown for purposes of illustration one form which my invention may assume in practice.

20 In these drawings,—

Fig. 1 is a diagrammatic view of the entire pumping system.

Fig. 2 is a central vertical section showing my improved controlling mechanism.

25 Fig. 3 is a detail sectional view of the displacement unit.

Fig. 4 is a fragmentary view in end elevation of the control mechanism shown in Fig. 2.

In the illustrative embodiment of my improved pumping system a compressor 1 supplies compressed fluid through a pipe 2 to a receiver tank 3. From the receiver tank compressed fluid is conducted through a pipe 4 and valve 5 to the air line 6 which leads to the displacement unit 7 in the well. The displacement unit which I have shown comprises a U-shaped member or footpiece 8 provided with check valves 10 and 9 on one side and in the bottom of the footpiece. A tail pipe 11 is connected to the bottom of the U-shaped member while into one of the upward openings the discharge pipe 12 is fitted and into the other upward opening is fitted one end of a filling chamber or displacement tank 13 which in turn is connected to the air line

6. Any other type of displacement unit may be substituted for the one shown and described, for example, the ordinary displacement barrel. At the top of the discharge pipe 12 is shown a pipe 12^a provided with an outwardly opening check valve 14 for conducting liquid to wherever it is desired to be pumped as, for example, into elevated tanks.

My improved controlling mechanism includes a pair of cylinders 15 and 16, the former being termed the operating cylinder and the latter the dashpot cylinder. The cylinder 15 is connected to the discharge pipe 12 in any suitable manner and has therein a plunger 15^a which carries at its upper end a crosshead 17 which is also rigidly connected to the dashpot piston 18 in the dashpot cylinder. This plunger also carries at its upper end a weight 19 for normally maintaining the same in its lower position as shown in Fig. 2 until operated on by fluid pressure in the discharge pipe 12.

Since the operating plunger and dashpot piston are interconnected by the crosshead 17 the rate of movement of one may be controlled by the rate of movement of the other. For controlling the movement of the dashpot piston I have employed suitable by-pass pipes 20, 21 and 22. The pipes 20 and 21 each have downwardly opening check valves 23 and 23' and regulating valves 24 and 24' respectively for controlling the upward movement of the crosshead 17. The pipe 22 also has a regulating valve 25 and an upwardly opening check valve 26 for controlling the rate of movement of the crosshead 17 in a downward direction and has two points of communication with the lower end of the dashpot cylinder. Means are provided between the crosshead 17 and the valve 5 whereby movement of the crosshead 17 controls the piston of said valve. A valve 27 is also provided in the air line 6 which is connected to the atmosphere at 28 for the purpose of exhausting the displacement unit to the atmosphere. The operation of this valve

is also controlled by the position of the cross-head 17. The valves 5 and 27 are of the fluid pressure operated diaphragm type, the valve 5 adapted to be held open by fluid pressure on its diaphragm 29, while the valve 27 is adapted to be held closed by fluid pressure on its diaphragm 30. Any suitable gravity operated mechanisms 31 and 32 may be employed for holding these valves in the position opposite to that in which the fluid pressure tends to hold them. Compressed fluid is transmitted through the line 33, stop valve 33^a and regulating valve 34 to a cylinder 36 having a pilot valve 37 therein, the position of which is controlled by the crosshead 17. This pilot valve cylinder has three additional openings, one for connection to each of the valves 5 and 27 by way of pipes 38 and 39, and a third connected to the atmosphere at 40. Adjustable stops 41 and 42 on the pilot valve rod 43 provide a lost motion connection between the crosshead 17 and the pilot valve. The form of pilot valve which I have illustrated is of the balanced piston type having balancing passages 44 therethrough, but of course any other valve which is capable of performing the required operations may be used. A gland 45 is shown to provide sufficient friction to hold the valve in its different positions, but any other suitable means might be used.

The operation of my device may be described as follows: Assuming that the relative position of the parts is, save that valve 5 is closed and valve 27 open, as shown in Fig. 2, when the operating piston is at its lower position and the level of liquid has risen in the displacement unit and filled the chamber 13, the stop valve 33^a is opened, admitting pressure fluid from the line 4 through the pilot valve cylinder 36 to the diaphragms 29 and 30. The valve 5 is then opened and the valve 27 closed, whereupon pressure fluid flows through the line 6 to the filling chamber 13, creating a pressure in the displacement member which seats the valve 9, opens the valve 10 and forces the accumulated charge of liquid upwardly through the discharge pipe 12. The operating plunger 15^a begins to rise at the time when the pressure of the liquid or the air compressed ahead of it is sufficient to overcome the counter-balance weight 19. Assuming now that the valve 24 is open, fluid from above the dashpot piston will flow past the check valve 23 to the lower end of the cylinder, allowing the piston to be moved upwardly at a fairly rapid rate provided the valve 24 is adjusted to permit a rapid flow. This causes the crosshead 17 to move upward to engage the stop 41 and lift the pilot valve to open the line 38 to the atmosphere, thereby closing the valve 5 and cutting off the supply of pressure fluid to the displacement unit. The expansive action of the air is then taken ad-

vantage of to complete the operation of ejecting the liquid and the interval of time through which this expansion may take place is controlled by regulating the rate of further upward movement of the piston 18 and pilot valve 37. This regulation is accomplished by means of the valve 24' which is preferably adjusted so as to allow only a restricted flow in order that the power medium may be used expansively. By the appropriate adjustment of the valve 24' the venting of the chamber 13 may be effected before the liquid is entirely discharged therefrom. By the time the liquid has all been discharged past the valve 14 the pilot valve 37 will have moved upwardly a sufficient distance to open the line 39 to the atmosphere whereupon the valve 27 is opened. The pressure in the discharge pipe 12 then falls to such an extent that the weight 19 begins to move the plunger 15^a downwardly. During this downward movement of the plunger 15^a another charge of liquid is accumulating in the filling chamber 13 and it is therefore desired to control this movement so as to allow sufficient time to elapse for the chamber to be completely filled. For this purpose the by-pass pipe 22 and regulating valve 25 is provided which controls the total downward stroke of the plunger. It will be noted that when the crosshead 17 moves against the stop 42 the pilot valve 37 will again be moved downward, first admitting pressure fluid to the valve 27 and closing the same and later opening the valve 5 to again supply pressure fluid to the line 6 and displacement member 7 for forcing out another charge of liquid, and the same cycle of operations as above described is repeated during the normal operation of the system. By using the double communication with the dashpot cylinder the movement effecting closure of the vent valve 27 and opening of supply valve 5 may be made fairly rapid, thereby eliminating loss of time when neither filling nor emptying is in process.

It will be noted that when the parts are in the position shown in Fig. 2, if the valve 24 is closed, the supply valve 5 will be held continuously open and the system would operate as an air-lift pump. This feature is particularly advantageous in wells where the available static head is at times sufficient for efficient air-lift pump performance, while at other times the head and therefore the submergence of the footpiece is so reduced that displacement pump operation is more efficient.

While I have in this application specifically described one form which my invention may assume in practice, it will be understood that this form of the same is shown for purposes of illustration and that the invention may be modified and embodied in various

other forms without departing from its spirit or the scope of the appended claims.

What I claim as new and desire to secure by Letters Patent is:

5. 1. In a liquid pumping apparatus of the single unit displacement type for raising and discharging liquid against pressure, a filling chamber having check valves and a discharge pipe associated therewith, a pressure fluid line leading to said filling chamber, means for automatically closing said line when liquid has been flowing from said chamber for a certain time interval, independently movable means for relieving the pressure in 10 said filling chamber for a certain time interval after discharge during the filling operation, automatic means for reopening the air line to again eject the liquid from the filling chamber, and adjustable means for independently regulating each of said time intervals to suit different operating conditions.
2. In a displacement pump, a displacement unit, a pressure fluid line leading thereto, a valve in said line for controlling admission of pressure fluid to said displacement unit, a separate valve for connecting said displacement unit to exhaust, and automatic means responsive to discharge of liquid from said unit for operating said valves at different times and properly timed relation.
3. In a displacement pump for raising liquid and discharging it against pressure, a displacement unit, means for supplying pressure fluid thereto, separate means for exhausting the same, valves for controlling said supply and exhaust means, and common control means for opening and closing said valves periodically, said valves operating at different times and in properly timed relation in response to discharge of fluid from the displacement unit.
4. In a pumping system for discharging liquid against substantial pressure, a displacement unit, means for supplying pressure fluid thereto to eject liquid therefrom, exhaust means for relieving fluid pressure in said unit during the filling operation, said unit also having a liquid discharge pipe connected thereto, valve means automatically operated in response to variations in pressure in said discharge pipe for controlling the supply and exhaust, and control means for regulating said valve means so as independently to control the time of cut-off, exhaust and admission.
5. In a pumping system for discharging liquid against substantial pressure, a displacement unit, means for supplying pressure fluid thereto to eject liquid therefrom, exhaust means for relieving fluid pressure in said unit during the filling operation, said unit also having a liquid discharge pipe connected thereto, valve means for controlling said supply and exhaust, and means for automatically operating said valve means in response to variations of pressure in said discharge pipe comprising an operating cylinder connected to the discharge pipe, an operating piston therein, a resistance to movement of said piston, means operatively associated with said valve means and controlled by the position of said piston, and means for adjusting said resistance to control the time of admission and exhaust.
6. In a pumping system for discharging liquid against substantial pressure, a displacement unit, means for supplying pressure fluid thereto to eject liquid therefrom, exhaust means for relieving fluid pressure in said unit during the filling operation, said unit also having a liquid discharge pipe connected thereto, valve means for controlling said supply and exhaust, and means for automatically operating said valve means in response to variations of pressure in said discharge pipe comprising an operating cylinder connected to the discharge pipe, an operating piston therein, a dashpot cylinder having a piston therein, said pistons being interconnected, means associated with said dashpot cylinder for controlling the rate of movement of said pistons upwardly and downwardly independently, and an operative connection between said pistons and said valve means.
7. In a pumping system for discharging liquid against substantial pressure, a displacement unit, means for supplying pressure fluid thereto to eject liquid therefrom, exhaust means for relieving fluid pressure in said unit during the filling operation, said unit also having a liquid discharge pipe connected thereto, independently operable valves for controlling said supply and exhaust, and fluid pressure means for automatically operating said valve means and means including a plunger actuated directly by pressure in said discharge pipe for controlling said fluid pressure means.
8. In a pumping system for discharging liquid against substantial pressure, a displacement unit, means for supplying pressure fluid thereto to eject liquid therefrom, exhaust means for relieving fluid pressure in said unit during the filling operation, said unit also having a liquid discharge pipe connected thereto, separate valve means for controlling said supply and exhaust, and separate fluid pressure operated means for automatically operating said valve means and controlling means for said fluid pressure means including a plunger actuated directly by pressure in said discharge pipe, a pilot valve operated by movement of said plunger, and adjustable means for controlling the rate of movement of said plunger and pilot valve.
9. In a pumping system for discharging liquid against substantial pressure, a displacement unit, means for supplying pressure fluid thereto to eject liquid therefrom, ex-

haust means for relieving fluid pressure in said unit during the filling operation, said unit also having a liquid discharge pipe connected thereto, valve means for controlling said supply and exhaust, and means for automatically operating said valve means in response to variations of pressure in said discharge pipe comprising an operating cylinder connected to the discharge pipe, an operating piston therein, a dashpot cylinder having a piston therein, said pistons being interconnected, means associated with said dashpot cylinder for controlling the rate of movement of said pistons, and an operative connection between said piston and said valve, said rate controlling means comprising bypass passages for permitting fluid in said dashpot cylinder to flow from one side of the piston to the other, one of said bypasses permitting flow of fluid in only one direction and another of said bypasses permitting flow of fluid in only the opposite direction.

10. In a pumping system for discharging liquid against substantial pressure, a displacement unit, means for supplying pressure fluid thereto to eject liquid therefrom, exhaust means for relieving fluid pressure in said unit during the filling operation, said unit also having a liquid discharge pipe connected thereto, valve means for controlling said supply and exhaust, and means for automatically operating said valve means responsive to pressure in said discharge pipe comprising an operating cylinder connected to the discharge pipe, an operating piston therein, a dashpot cylinder having a piston therein, said pistons being interconnected, means for controlling the rate of movement of said pistons comprising a plurality of 25 valved by-pass passages communicating with the dashpot cylinder permitting flow of fluid from one side of said dashpot piston to the other in only one direction and a single valved passage permitting flow in only the reverse direction, and an operative connection between said pistons and said valve means.

11. In a pumping system for discharging liquid against substantial pressure, a displacement unit, means for supplying pressure fluid thereto to eject liquid therefrom, exhaust means for relieving fluid pressure in said unit during the filling operation, said unit also having a liquid discharge pipe connected thereto, valve means for controlling said supply and exhaust, and means for automatically operating said valve means responsive to pressure in said discharge pipe comprising an operating cylinder connected to the discharge pipe, an operating piston therein, a dashpot cylinder having a piston therein, said pistons being interconnected, means for controlling the rate of movement of said pistons comprising a plurality of valved by-pass passages communicating with the dashpot cylinder permitting flow of fluid from one

side of said dashpot piston to the other in one direction and a single valved passage permitting flow in the reverse direction, and an operative connection between said pistons and said valve means, one of said passages adapted to be closed whereby pressure fluid is continuously supplied to said displacement unit for operating the system as an air lift pump.

12. In a displacement pumping system, a displacement tank having check valves and a discharge pipe associated therewith, a supply line for supplying actuating fluid to said tank, means for automatically cutting off said supply after liquid has been discharging under full pressure from said tank for a certain time interval, means for connecting said tank to exhaust a definite time after said cutting off operation so as to permit expansive action of said actuating fluid, said exhaust connection being maintained open for a definite time interval to permit filling of said tank, and means for separately controlling the periods of exhaust, admission and expansion.

13. In a displacement pumping system, a single displacement tank having a check-valved discharge pipe associated therewith, means for supplying actuating fluid to said tank to initiate, and to maintain while said supply continues, discharge of liquid through said discharge pipe, means independent of the liquid level in said tank for automatically interrupting actuating fluid supply substantially subsequent to the initiation of discharge of liquid by said actuating fluid but while said tank is still partially full, and means, operative only after a further substantial period of liquid discharge but prior to complete emptying of said tank, for automatically connecting said tank to exhaust independently of said discharge pipe.

14. In a displacement pumping system, a single displacement tank having a check-valved discharge pipe associated therewith, and means for controlling the filling and emptying of said tank including means for supplying actuating fluid to said tank to initiate, and to maintain while said supply continues, discharge of liquid through said discharge pipe, means independent of the liquid level in said tank for automatically interrupting the supply of actuating fluid substantially subsequent to the initiation of discharge of liquid by said actuating fluid but while said tank is still partially full, and means operative only after a further substantial period of liquid discharge but prior to complete emptying of said tank for automatically connecting said tank to exhaust independently of said discharge pipe, said controlling means including means for separately varying the period of supply of actuating fluid to said tank after liquid discharge commences and the period intervening between

interruption of actuating fluid supply and the connection of said tank to exhaust.

15. In a pumping system for raising liquid and discharging it against pressure, a pumping chamber, means for supplying actuating fluid thereto and for venting the same to permit filling, and controlling means for said actuating fluid supplying means and venting means including a plunger moved by pumped liquid in one direction and connected for communication with the pumped liquid to effect substantially immediate cessation of the contact of said plunger with the pumped liquid on cessation of the pumping operation.

15. In a displacement pumping system, a displacement tank having check valves and a discharge pipe associated therewith, a supply line for supplying actuating fluid to said tank, means dependent upon the discharge of liquid from said tank for automatically cutting off said supply after liquid has been discharging under full pressure from said tank for a certain time interval, means for connecting said tank to exhaust a definite time 25 after said cutting off operation so as to permit expensive action of said actuating fluid, said exhaust connection being maintained open for a definite time interval to permit filling of said tank, and means for separately 30 controlling the periods of exhaust, admission and expansion.

17. In a displacement pumping system, a displacement tank having a check-valved discharge pipe associated therewith, means for supplying actuating fluid to said tank to initiate, and to maintain while said supply continues, discharge of liquid through said discharge pipe, means independent of the liquid level in said tank but dependent upon the discharge 35 of liquid from said tank for automatically interrupting actuating fluid supply substantially subsequent to the initiation of discharge of liquid by said actuating fluid but while said tank is still partially full, and 40 means, operative only after a further substantial period of liquid discharge but prior to complete emptying of said tank, for automatically connecting said tank to exhaust independently of said discharge pipe.

50. 18. In a displacement pumping system, a displacement tank having a check-valved discharge pipe associated therewith, and means for controlling the filling and emptying of said tank including means for supplying actuating fluid to said tank to initiate, and to maintain while said supply continues, discharge of liquid through said discharge pipe, means independent of the liquid level in said tank but dependent upon the discharge of 55 liquid from said tank for automatically interrupting the supply of actuating fluid substantially subsequent to the initiation of discharge of liquid by said actuating fluid but while said tank is still partially full, and 60 means operative only after a further substan-

tial period of liquid discharge but prior to complete emptying of said tank for automatically connecting said tank to exhaust independently of said discharge pipe, said controlling means including means for separately varying the period of supply of actuating fluid to said tank after liquid discharge commences and the period intervening between interruption of actuating fluid supply and the connection of said tank to exhaust. 70

In testimony whereof I affix my signature.
